[57] ABSTRACT

A digital output current comparing device comprises two sets of transistors of opposed types, the emitters and bases of the transistors of each set being in common. Two currents to be compared are supplied to the collectors of the first transistors of each set which each have their collector and base connected and are so dimensioned that they cannot saturate or block. The collectors of the other transistors of each set are each connected to the collector of a corresponding transistor of the other set and to a respective output, the effective injection surface areas of the base-emitter junctions of the transistors of each set being selected so that each output changes state (logic 1 or 0) for a given value of the ratio of the currents to be compared.

CURRENT COMPARING DEVICE

The invention relates to electric current comparing devices.

Many known current comparing devices operate in a continuous or analog manner and are adapted either to display the results or to directly or indirectly control adjusting or monitoring devices.

However, for certain applications, the current comparing device should be adapted to supply the result of comparison in the form of digital data compatible with subsequent treatment by logic means.

The invention therefore provides a device for comparing two currents and supplying the result in an all-or-none digital form, which comprises two sets of transistors of opposed types, the emitters and bases of the transistors of each set being in common, the collector of a first transistor of each set being connected to a respective source of one of two currents to be compared, and means for preventing saturation and blocking of said first transistors, the collector of each of the other transistors one in each set being connected to the collector of a corresponding transistor of the other set and to a respective output of the device, the characteristics of the transistors of each set being chosen in such a manner that each of the outputs changes state for a given value of the ratio of the currents to be compared.

The connection in common of the emitters and bases of each set of transistors enables the use of high value resistors to be avoided, even in the case of use with very low current. The device according to the invention is thus suitable for manufacture by integrated-circuit techniques.

An embodiment of a device according to the invention for comparing two currents will now be described, by way of example, with reference to the accompanying drawings, in which:

FIG. 1 is a circuit diagram thereof;

FIG. 2 shows the current-voltage characteristics of a pair of complementary transistors whose collectors are connected together;

FIG. 3 is an explanatory diagram showing the form of the output signals as a function of the ratio of the currents to be compared;

FIG. 4 shows a variation of the circuit shown in FIG. 1;

FIG. 5 schematically shows an integrated circuit structure incorporating the p-n-p transistors of FIG. 1;

FIG. 6 is a schematic diagram illustrating an application of the device of FIG. 1; and

FIG. 7 is an explanatory graph illustrating the operation of the comparing device as used according to FIG. 6.

The circuit shown in FIG. 1 comprises two sets of transistors TN_0 to TN_n and TP_0 to TP_n , respectively of n-p-n and p-n-p types. The bases of the transistors of each set are interconnected together, as are the emitters. The collector of each transistor TN_k (where k is from 1 to n) is connected to that of the corresponding transistor TP_k , while the collectors of transistors TN_0 and TP_0 are connected to their own bases. The currents I_a and I_b to be compared are applied to the collectors of the transistors TN_0 and TP_0 respectively. An output terminal S_k (where k is from 1 to n) is connected to the common collector of each pair of transistors TP_k and TN_k .

2

For the purposes of explanation of the operation, let us suppose for the time being that the base currents of all of the transistors may be neglected.

The collector and emitter currents of transistor TN_0 are thus equal to I_a . Since the voltage of the collector of transistor TN_0 is equal to its base voltage, it operates in the non-saturated phase. The transistors TN_0 to TN_n are connected so that their base-emitter voltages are all the same. Moreover, they are simultaneously manufactured in the same integrated circuit. Consequently, the collector current of each non-saturated transistor TN_k (where k is here from 0 to n) is proportional to its dimensions or more precisely to the effective injection surface area AN_k of its base-emitter junction. The collector current of the non-saturated transistor TN_k is thus equal to

$$I_a AN_k / AN_0$$

FIG. 2 shows the characteristic of one of the set of n-p-n transistors TN_k for which k is from 1 to n , the collector voltage U_c being shown along the abscissa and the collector current I_c along the ordinate.

The complementary p-n-p transistors are connected together in an exactly analogous manner. The collector current of the non-saturated transistor TP_k , where k is from 1 to n , is proportional to its effective injection surface area AP_k , and is thus equal to

$$I_b AP_k / AP_0$$

Transistor TP_k forms the load of the corresponding transistor TN_k . Its output characteristic is shown in broken lines in FIG. 2 for the two following cases:

$$I_b AP_k / AP_0 > I_a AN_k / AN_0$$

(1)

$$I_b AP_k / AP_0 < I_a AN_k / AN_0$$

(2)

The quiescent point of the structure formed by the series connection of TP_k and TN_k between the terminals $+U$ and 0 is given by the intersection of the output characteristic of TN_k (full line) with that of TP_k (broken line) and corresponds to the following conditions:

Case 1:

TP_k saturated

TN_k non-saturated

Current I_k through the pair of transistors k :

$$I_k = I_a AN_k / AN_0$$

Potential of output S_k close to $+U$ (logic 1).

Case 2:

TN_k saturated

TP_k non-saturated

Current I_k through the pair of transistors k :

$$I_k = I_b AP_k / AP_0$$

Potential of output S_k close to 0 (logic 0).

The transition from case 1 to case 2, i.e., the passage of output S_k from the logic state 1 to the logic state 0 takes place for

$$I_a AN_k / AN_0 = I_b AP_k / AP_0$$

thus

$$I_b/I_a = (AN_k/AN_0)(AP_0/AP_k)$$

By appropriating selecting the relative dimensions of the n-p-n transistors and the relative dimensions of the p-n-p transistors, it can be arranged that each output S_k changes state for a selected ratio I_b/I_a .

For example, if

$$AN_0 = AN_1 = \dots = AN_n$$

and $AP_0 = AP_1 = 2AP_2 = 3AP_3 = \dots = nAP_n$
then S_1 will switch for $I_b/I_a = 1$

S_2 will switch for $I_b/I_a = 2$
and S_n will switch for $I_b/I_a = n$.

The states (output voltages) S_1 to S_n for this example are shown in FIG. 3 as a function of the ratio I_a/I_b .

The logic data (0 or 1) supplied according to the states of outputs S_1 to S_n may be subsequently treated by logic circuits, not shown, for example MOS transistors.

The above explanations are based on the assumption that the base currents of the transistors may be neglected in relation to the currents I_a and I_b to be compared.

In reality, when a transistor saturates, its base current may become comparable to its collector current, since the reverse gain of a transistor is generally low. Consequently, if the collector currents are themselves of comparable value to I_a and I_b , the base currents are not negligible as had been assumed above.

To ensure that the base currents TN_1 to TN_k do not make measurement of the current ratio I_a/I_b inexact, it is necessary to avoid by-passing an appreciable proportion of the currents to be measured from the collector circuit of transistors TN_0 and TP_0 . Several solutions will now be set forth.

The first solution is to arrange the dimensions of the transistors so that:

$$AN_0 >> AN_1 \dots AN_n$$

$$AP_0 >> AP_1 \dots AP_n.$$

The currents I_a and I_b are thus much greater than the collector currents of the transistors liable to saturate. The base currents will remain negligible if the normal gains of the transistors are sufficiently high.

A second solution consists of adding amplifying transistors TN_a and TP_a in the base circuits (see "Handbook of Semiconductor Electronics," L.P. Hunter, 1970, P 10-12), as shown in FIG. 4. If the current gain B_a of transistor TN_a (FIG. 4) is high, the fraction $1/B_a$ of the sum of the base currents of transistors TN_0 to TN_n subtracted from I_a is negligible. The transistor TP_a acts in the same manner.

To provide the above-described devices in integrated circuit form, n-p-n transistors of conventional structure and p-n-p transistors of so-called "lateral" structure may, for example be, used. The latter are schematically shown in FIG. 5 for the case $n = 4$.

In an n-type semi-conductor block forming the common base B of all of the p-n-p transistors (except the auxiliary transistor TP_a of FIG. 4) are diffused p-zones, shown in hatching in FIG. 5. Zone E forms the common emitter, and is surrounded by the collectors C_0 , C_1 , C_2 , C_3 , C_4 of the transistors TP_k ($k = 0$ to 4).

If one of the transistors, for example TP_4 , is saturated, its collector C_4 injects carriers (holes) into the base region. If the neighboring transistor, TP_2 in this example, is not saturated, its collector C_2 risks collecting

a part of these carriers, which would make the operation of the device inexact. To avoid this possibility, a "guard" collector C, separating the other collectors, is added. This guard collector C is connected to 0 potential. It will collect the carriers injected by a collector, thus preventing them from reaching the adjacent collector. The efficient injection sectional area AP_0 , AP_1 , $AP_2 \dots AP_k$ of each transistor is proportional to the corresponding length l_0 , l_1 , $l_2 \dots l_n$ shown in FIG. 5.

- 10 The described device may be used both for the comparison of currents and for the comparison of resistor values. With reference to FIG. 6, to compare the values of two resistors R_f and R_v , the first resistor R_f , through which a current I_a passes, is connected to a voltage $+U$, and the second resistor R_v , through which a current I_b passes, is connected to ground. Since the voltage drops in transistors TN_0 and TP_0 are practically equal, the voltages at the terminals of the two resistors will also be equal. The ratio of the values of the resistors is given by:

$$R_f/R_v = I_b/I_a. \text{ The measurement of this ratio is practically independent of the applied voltage } U.$$

25 The value of one or both of resistors R_f and R_v may in turn depend on other quantities. Thus, a possible application of the device of FIG. 6 is as a thermometer with a digital output, by making the value of resistor R_f fixed, and the value of resistor R_v variable with the temperature. The ratio I_b/I_a is thus made to vary with the temperature, but only extremely slightly with the supply voltage U .

30 The variation of the ratio I_b/I_a is not necessarily a linear function of the temperature. By suitably selecting the dimensions of the various transistors of the comparing device, it is however possible linearize its output, i.e., obtain switching of the different outputs S_k at equal steps of temperature, as indicated in FIG. 7.

35 Another application, now shown, is as a stress sensor. In this case, the two resistors R_f and R_v (FIG. 6) are identical and manufactured on a single support in order to balance thermal effects. Resistor R_v is oriented in a manner such that it varies with a certain applied stress, while resistor R_f is oriented, for example perpendicularly to R_v , so that it does not depend on said stress.

40 Another application, also not shown, is as a digital output photometer. I_a is thus a constant or reference current, and I_b a current through a photoelement, for example a photodiode or photoresistor.

45 What is claimed is:

1. Digital output current comparing device, comprising two sets of transistors of opposed types each transistor having an emitter, a base and a collector, the emitters and bases of the transistors of each set being in common, the collector of a first transistor of each set being connected to a respective source of one of two currents to be compared, means for preventing saturation and blocking of said first transistors, the collector of each of the other transistors of each set being connected to the collector of a corresponding transistor of the other set and to a respective output, and the characteristics of the transistors of each set being selected so that each of said outputs changes state for a given value of the ratio of the currents to be compared.

2. Device according to claim 1, in which the pairs of other transistors are complementary two pole transistors in an integrated circuit.

3. Device according to claim 2, in which the transis-

tors of one set are p-n-p transistors of lateral structure.

4. Device according to claim 3, in which the collectors of the lateral p-n-p transistors are separated from one another by a guard collector forming means for preventing carriers injected by the collector of a saturated one of said p-n-p transistors from being collected by the collector of another of said p-n-p transistors.

5. Device according to claim 1, in which the characteristics of the transistors of at least one of said sets are selected by means of their geometry.

6. Device according to claim 5, in which said first transistor of each set has its collector connected to its base and dimensions substantially greater than those of the other transistors of the respective set to make the base currents of saturated transistors negligible and lower the overall current consumption.

7. Device according to claim 1, comprising amplifying

means between the collector and base of said first transistor of each set.

8. Device according to claim 1, in which said values of the ratio of the currents to be compared for which each output changes state differ by the same amount between successive outputs.

9. Device according to claim 1, in which the ratio of currents to be compared is determined by a ratio of resistances.

10. Device according to claim 1, in which at least one of the currents to be compared varies as a function of a physical quantity.

11. Device according to claim 10, in which the differences in value of said physical quantity corresponding to changes in state of successive outputs are all equal.
